SECTIONAL WINDOW DRAPERY

Alfred J. Dubinsky, La Crosse, Wis.

Application May 11, 1951, Serial No. 225,771

6 Claims. (Cl. 160—231)

1

This invention relates to new and useful improvements in draperies, and more particularly to draperies of the general type disclosed in my co-pending application, Serial No. 199,000, filed December 4, 1950.

One of the important features of the present invention resides in the novel means employed for securing together the contiguous edges of adjacent drape sections whereby the joint therebetween is substantially concealed from view from both sides of the composite drapery, when hung.

According to the present invention, an independent connecting element is employed for securing together the edges of adjacent drape sections. This connecting element is preferably composed of an elongated strip of relatively stiff fabric, such as buckram, which is apertured along its opposed side edge portions the length of the strip, thereby to permit the male fastening elements of conventional snap buttons secured to the marginal edges of the drape sections, to be inserted through the apertures in the connecting element into locking engagement with their complementary female fastening elements, secured to the vertical edge portions of the drape lining sections, thereby to secure together adjacent drape and liner sections in a manner whereby the buckram connecting element is substantially concealed from view, between the liner and the drape sections, so that when the connected drape and liner sections are subsequently hung, they may have the appearance of a one-piece drape.

An important object of the present invention, therefore, resides in the provision of an independently constructed flexible securing element adapted to be interposed between the drapery and liner sections, when the liners are secured to the draperies.

A further object is to provide a sectional drapery having means whereby adjacent drape sections may be detachably secured together with their edges disposed in abutting relation, and whereby the composite drapery may simulate a single drapery.

A further object is to provide a connecting element for detachably securing together the contiguous edges of a pair of drape sections, said connecting element being in the form of an elongated ribbon-like strip which is adapted to be inserted between the overlapping edge portions of the drape and liner sections, so that the snap buttons provided on the edges of the drapery and liner sections, when engaged with one an-

2

other, may pass through apertures provided in the connecting element, thereby to connect together in abutting relation, the contiguous edges of a pair of drapery sections and their liners, to provide, in effect, a one-piece drapery wherein the joints between adjacent sections are substantially concealed from view.

A further object is to provide a connecting element for detachably securing together adjacent drapery sections, said element having spaced apertures therein for receiving the projecting portions of male snap buttons preferably secured to the drape sections, when said snap buttons are operatively engaged with their complementary female snap buttons secured to the liner sections, or to strips of fabric, preferably of the same material as that of the drape sections, whereby the connecting element is completely concealed from view.

A further object is to provide a sectional drape comprising a simple inexpensive connecting element for connecting together the contiguous edges of adjacent drape sections, which element is extremely simple in construction and readily lends itself for manufacture in strip or tape form, whereby it may be wound into rolls to conserve space in storage.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is an inside view of a drapery comprising two sections having their contiguous edges secured together in abutting relation with the novel connecting element herein disclosed;

Figure 2 is an enlarged detail sectional view on the line 2—2 of Figure 1, showing the edges of the drape sections disposed in abutting relation, and the edges of the liners similarly disposed, with the connecting element completely concealed therebetween;

Figure 3 is a view similar to Figure 2, but showing the parts separated from one another;

Figure 4 is a view showing the connecting element detached from the drapery;

Figure 5 is a view showing a strap element used in conjunction with the connecting element for

securing together two drapery sections when no liners are utilized;

Figure 6 is a view showing the two drapery sections connected together with the connecting element and the strap elements illustrated in Figure 5 being utilized to conceal the connecting element; and

Figure 7 is a view similar to Figure 2, showing a modified construction.

In Figure 1 there is illustrated a composite drapery composed of two drape sections 2 and 3, having tapes 4 secured to their vertical edges to provide anchors for a plurality of male snap buttons 5 spaced equi-distant apart the length of each tape.

The drapery illustrated in Figure 1 is shown provided with a lining, generally designated by the numeral 10, and comprising two sections 6 and 7, which, like the drape sections, have tapes 8 secured to the vertical edges thereof to provide anchors for a plurality of female snap buttons 9, secured thereto in spaced relation and adapted to register with the male snap buttons 5 in the tapes 4 of the drape sections.

The essential difference between the structure disclosed in the present application, and the structure disclosed in my co-pending application, hereinbefore mentioned, is that in the present application, an independent, or separable connecting element is utilized for connecting together the contiguous edges of adjacent drapery sections. To connect together the contiguous edges of adjacent drape sections, as herein disclosed, a connecting element, generally designated by the numeral 11, shown in Figure 4, is provided. This element is shown having two rows of apertures 12 therein, spaced apart lengthwise of the element to register with the snap buttons in the drape and liner sections, when the element 11 is applied thereto.

When it is desired to connect together the vertical edges of two drape sections, said sections are arranged with their edges disposed in abutting relation, as shown at A in Figure 3. The connecting element or strip 11 is then placed over the adjacently disposed tapes 4 of the drape sections, as will be understood by reference to Figures 1, 2 and 3, with the male snap buttons being received in the apertures 12 of the connecting element. The female snap buttons 9 of the liner sections are then pressed into interlocking engagement with their complementary male snap buttons, as shown in Figure 2, thereby operatively connecting together the vertical edges of the drape sections 2 and 3, and at the same time securing the liner sections 6 and 7 to the drape sections. When the drape and liner sections are thus connected together the connecting element 11 and snap buttons 5-9 are completely concealed from view from both sides of the composite drapery.

A snap button anchoring tape 13, similar to the tapes 4, is secured to the upper portion of each drape section, as best illustrated in Figure 6, and support a plurality of male snap buttons 5 adapted to interlockingly engage a plurality of female snap buttons 9 provided on the upper horizontal edges of the liner sections 6 and 7, as will be understood by reference to Figure 1.

When the composite drapery is to be utilized without a lining, a plurality of covering straps 15, shown in Figure 5, are utilized. The covering straps 15 have female snap buttons 9 secured thereto which are spaced apart the length of each tape to correspond to the spacing between the

male snap buttons secured to the vertical edges of the drape sections 2 and 3.

When a drapery is to be hung without a lining, two or more drape sections are arranged with their contiguous edges abuttingly engaged, or substantially so, as illustrated at A in Figure 3. The connecting element 11 is then placed over the male snap buttons 5 of the drape sections, after which the covering straps 15 are placed over the connecting element 11, as shown in Figure 6, and the female snap buttons 9 thereof pressed into locking engagement with the male snap buttons 5 of the drape sections. By thus attaching the covering straps to the male snap buttons of the drape sections 2 and 3, the connecting element 11 is securely secured in position between the two drape sections and is completely concealed by the covering straps, as shown in the upper portion of Figure 6. The covering straps 15 serve a dual function in that the female snap buttons 9 thereof cooperate with the male snap buttons 5 of the drape sections to secure the connecting element 11 in place between the drape sections, and, at the same time, the covering straps completely conceal the element 11 and all of the snap buttons engaged therewith.

The connecting element herein disclosed greatly facilitates the operation of detachably connecting together the contiguous edges of a pair of drape sections and liners. The connecting element 11, being made of a relatively stiff material, such as buckram, may readily be handled in the operation of placing it over the male snap buttons secured in the edges of the drape sections, whereby said connecting element will hold the drape sections together while the liner sections 6 and 7, or the covering straps 15 are secured to the drapes, depending upon whether or not the completed drapery is to be lined or unlined.

In the manufacture of the drapes, the snap buttons, both male and female, are all spaced the same distance apart on their respective supporting tapes, whereby the drape sections may be utilized interchangeably. This is a highly desirable feature in a sectional drapery of this general type. The connecting element 11 may readily be manufactured from sheet stock and passed through a suitable perforating machine for piercing the holes therein equi-distant apart the length of the strip, after which it may be wound into rolls to facilitate handling and storage, prior to use.

In Figure 7 there is illustrated a construction wherein a single element, generally designated by the numeral 16, is utilized for connecting together the contiguous edges of a pair of drape sections 2 and 3.

The connecting element 16 preferably comprises an inner ply 17 of a suitable material such as buckram, to which female snap buttons 18 are secured. To conceal the snap buttons and the joint between the drape sections 2 and 3, the inner ply, including the snap buttons 18, are covered with a suitable fabric 19, having its marginal side edges turned under and secured to the corresponding edges of the inner ply 17, as shown in Figure 7.

When using the connecting element shown in Figure 7, the two drape sections are arranged with their contiguous edges abuttingly engaged, as shown, and the connecting element 16 is then snapped into engagement with its complementary male snap buttons 5 on the drape sections, whereby the two sections are operatively con-

nected together, and all of the snap buttons utilized for making such connection are completely hidden or concealed by the connecting element 16. If desired, the strip of buckram may be eliminated, and a strip of drapery fabric utilized in lieu thereof. When such fabric is used, it is preferably folded upon itself to render the connecting element sufficiently stiff to facilitate its application to the drape sections, and also for the purpose of concealing the snap buttons 18 from view.

While I have herein illustrated and described the invention as utilized in connection with a sectional drapery, it is to be understood that it is capable of variations and modifications without departing from the spirit of the invention. I therefore do not wish to be limited to the specific construction disclosed, provided the connecting means between the drape sections is so constructed that the fastening elements, such as the snap buttons, are completely concealed from view when the draperies are hung.

The foregoing detailed description has been given for clearness of understanding only, and no unnecessary limitations should be understood therefrom, but the appended claims should be construed as broadly as permissible in view of the prior art.

I claim as my invention:

1. A sectional drapery comprising two or more sections secured together along their contiguous edges, a plurality of fastening elements secured to the vertical edges of said drape sections and spaced equi-distant apart the length thereof, and an elongated ribbon-like connecting element having complementary fastening elements secured thereto adapted to be interlocked with the fastening elements on the contiguous edges of said drape sections, thereby to secure said edges together the full length thereof.

2. A sectional drape according to claim 1, wherein the connecting element is constructed of a relatively stiff but flexible material.

3. A sectional drapery according to claim 1, wherein the connecting element comprises an elongated strip of buckram having a plurality of fastening elements secured thereto for interlocking engagement with the fastening elements on the contiguous edges of adjacent drape sections, and said connecting element having its exposed side covered with drapery fabric, thereby to completely conceal the connecting element from view, when operatively engaged with the contiguous edges of adjacent drape sections.

4. A sectional drape comprising a plurality of like drape sections having a plurality of fastening elements secured to the vertical edges there-

of spaced equi-distant apart the lengths thereof, a connecting element having a plurality of apertures therein adapted to receive the fastening elements in the contiguous edges of adjacent drape sections, a lining for each drape section having complementary fastening elements secured to their vertical edges and spaced apart to register with the fastening elements secured to the drape sections, and whereby when the liner sections are placed against the drape sections and the fastening elements on one side edge of each liner section are interlocked with their complementary fastening elements on the adjacent edges of the drape sections, said connecting element is secured in position between the drape sections thereby to connect said drape sections together to provide a composite drapery wherein the connecting and fastening elements are completely concealed from view.

5. A sectional drapery according to claim 4, wherein the connecting element is constructed of an elongated strip of buckram having spaced perforations therein for receiving portions of the fastening elements for securing the liner sections 20 to the drape sections, and whereby said connecting element is concealed from view when in position between adjacent drape sections.

6. A sectional drapery comprising a plurality of like sections having fastening elements secured 30 to their vertical edges and spaced apart lengthwise thereof, a connecting element having a plurality of apertures therein for receiving the projecting portions of said fastening elements, thereby to connect together the contiguous edges of 35 adjacent drape sections, and covering straps each having a plurality of complementary fastening elements secured thereto in longitudinally spaced relation adapted to register with the fastening elements in the contiguous edges of the drape sections, said covering straps overlying the connecting element and their fastening elements interlocking with the fastening elements on the drapery sections, thereby to secure the connecting element in operative position between the 40 drape sections, said covering straps concealing the connecting element and all of said fastening elements.
